(57) **CLAIM**

The ornamental design for a solar dock light, as shown and described.

DESCRIPTION

FIG. 1 is a perspective view of a solar dock light design showing my new design.

FIG. 2 is a front view of a solar dock light.

FIG. 3 is a rear view of a solar dock light.

FIG. 4 is a left side view of a solar dock light.

FIG. 5 is a right side view of a solar dock light.

FIG. 6 is a top view of a solar dock light; and,

FIG. 7 is a bottom view of a solar dock light.

Any shading and cross-hatching are not features of the design but are utilized to illustrate the surface contours of the solar dock light design in the drawings.

The broken lines in the drawings depict portions of the solar dock light and form no part of the claimed design.
